CLAIM

I claim the ornamental design for a combined faucet and filter cap, shown and described.

DESCRIPTION

FIG. 1 is a front, right side perspective view of a combined faucet and filter cap showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures depict portions of the combined faucet and filter cap that form no part of the claimed design.
